ABSTRACT OF THE DISCLOSURE

A control valve or regulator mechanism for the dispensing head of a fluid dispensing system in which a valve assembly and an actuating assembly are disposed to coact with each other in assembled position and wherein the parts of at least the valve assembly are made of plastic materials and the valve assembly is adapted to regulate range of adjustability of the fluid flow rate of the volume of water passed by the dispensing head in which the control valve or regulator mechanism is mounted.

PRIOR ART

The prior art has come to recognize that in certain types of fluid distribution systems where the control valve is constantly subjected to use as for example in dispensers for cooled water, generally referred to as water cooler units, it is accepted practice to utilize a control valve which is in some form of cartridge unit adaptable to fit into a suitable cavity or bore in the dispensing head for the fluid dispensing unit.

Cartridge type control valves facilitate the repair and the replacement of parts for such control valves.

Control valves of the cartridge type are illustrated in U.S. Patents 3,089,510, 3,003,519, 2,868,223 and 1,793,292.

In the prior art cartridge type control valves, the best known of which are illustrated by U.S. Patents 2,868,223 and 3,003,519, the unit has acquired the "cartridge" definition, because the control valve is formed in an assembly independently of the dispensing head and the dispensing head control valve will be so manufactured and designed that the control valve can be placed into assembled position into the dispensing head, and of course, can be easily removed therefrom, when repairs are required.

These prior art cartridge type control valves, however, require particular materials to insure long life. Since brass and nickel-chrome alloys are adapted to withstand the corrosive and erosive effects of fluids such as water being dispensed, these units have been made up of this type of material.

Further, these cartridge type control valves require the application of the best techniques for providing close tolerances which will insure a device or mechanism not only adapted to effectively control the flow of fluid in the distribution or dispensing system in which the control valves operates but in addition, will operate without leakage, loss of pressure or other detrimental fluid system characteristics and such last mentioned characteristics must continue trouble free for prolonged period of time in order to provide a unit which is competitive with other existing units presently on the market.

These problems of high material costs and the application of precise manufacturing techniques, are under constant attack because each change in material and each step which reduces the problems of manufacture, generally will permit a reduction in cost of manufacture, a factor which even in terms of pennies, renders the sale of such improved control valves more competitive, as the marketing of these cartridge type control valves is

2

done in large volumes to manufacturers of dispensing units and fluid dispensing systems.

SUMMARY OF THE INVENTION

The present invention seeks to overcome these prior art problems by providing a multi-assembly control valve equivalent to the prior art cartridge type control valve wherein changes in material and manufacturing technique enable the unit to be manufactured with substantial cost savings.

This is accomplished in the present device, by changing the control valve into a plurality of assemblies and manufacturing at least the main elements of one of the assemblies of plastics.

It will be understood that while the present invention illustrates only the valve assembly as being made of plastic that it is within the scope of the present invention to have all the major elements of the control valve made of plastic.

Thus, the present invention covers an improved control valve for a fluid dispensing system including a valve assembly and a valve actuating mechanism adapted to coact with each other wherein said valve assembly includes, a bridge and a retaining ring to hold and mount said bridge in assembled position each made of a plastic material or the like type and a valve seat also of plastic mounted in a yoke type valve head; the valve head is formed on a stem in turn connected to the valve actuating mechanism to provide means to move the valve seat into and out of engagement with a valve outlet port in the bridge; the said bridge being further provided with an inlet which communicates with a source of fluid to be dispensed and passage means to deliver said fluid to the valve outlet port and the valve assembly having an outlet means in the form of a passage adapted to be sized relative the outlet port in the associate bridge to provide means to regulate the range of adjustability of the fluid flow rate of the volume of fluid passing through the control valve.

Accordingly, it is an object of the present invention to provide an improved multi-assembly control valve adapted to coact with a suitable dispensing means in a fluid system which is relatively cheap and easy to fabricate and provides substantial cost savings over prior art devices.

It is another object of the present invention to provide a control valve for a fluid dispensing system wherein at least the components forming the liquid or fluid passages and chambers are made of plastic or the like material and are easily assembled and adapted to coact with the remaining parts of the unit in assembled position.

Further objects and advantages of the invention will become apparent from a study of the following specification taken in connection with the accompanying drawings wherein,

FIGURE 1 is a perspective view of a dispensing head for a water cooler having a control valve in accordance with the present invention therein.

FIGURE 2 is a vertical cross-section of the dispensing head incorporating a control valve in accordance with the present invention.

FIGURE 3 is an exploded view of the various components of the valve in accordance with the present invention partly in vertical section and partly in side elevation.

FIGURE 4 is a cross-section taken on line 4—4 of FIGURE 2 showing the disposition of the bridge element in the retaining ring.

FIGURE 5 is a cross-section taken on line 5—5 of FIGURE 2.

FIGURE 6 is a perspective view of the bridge element of the valve assembly.

FIGURE 7 is a perspective view of the retaining ring 22 taken away partly in vertical section to show the construction thereof.

FIGURE 8 is a perspective view of the yoke member. FIGURE 9 is an enlarged view of a fragment of the FIGURE showing a modified form of valve port therefor. Referring to the drawings,

FIGURE 1 shows a control valve generally designated 10 in accordance with the present invention as applied to fluid dispensing head 2 of a conventional "push-ton" bubbler type water dispensing head of a conventional water cooler device presently utilized in offices, industrial establishments, etc.

It will be understood that this merely represents one preferred application for illustrating the control valve of the present invention and that the same is equally applicable to water faucets, globe valves, etc., as is illustrated example, at FIGURES 5 and 6 for the control valve shown in U.S. Patent 3,003,519.

Fluid dispensing head 2 will be bored to form a cavity 20 and a medially disposed sump or chamber 4. The sump chamber 4 opens into the floor of the cavity 3 and permits the cavity 3 and chamber 4 to receive the reversibly mounted control valve 1 of the present invention as is clearly shown in FIGURES 2 and 3 of the drawings.

The cavity 3 will connect to one end of an inlet passage 25 the remote end of which is threaded as at 6 to permit inlet passage 5 to be connected to any suitable source of fluid to be dispensed by the dispensing head and control valve 1 and to permit the fluid to be delivered through the control valve as hereinafter described. One end of an inlet passage 7 also communicates with the cavity 3 and the end of the outlet passage remote therefrom connects to a chamber 8 which supplies fluid to the dispensing outlet 9 in a nozzle assembly 10 detachably connected to the dispensing head 2 adjacent a water deflector or shield 11 as shown in FIGURES 1 and 2 of the drawings. The control valve 1 of the present invention is mounted in the cavity 3 and chamber means 4 or the dispensing head 2 by the interengaging threaded means 12 at the open or mouth end of the cavity 3 and the threaded means 13 on the control valve 1. These last mentioned threaded means 13 also serve to mount a push button retainer 14 in which the push button 15 is retained as shown in FIGURE 2 of the drawings. The push button 15 is held in an actuating position by abutment with the upper end of an actuating assembly generally designated 50 for the control valve 1 under the action of a push button return ring 16 about said actuating assembly all of which is more fully described hereinafter.

The actuating assembly 50 of the control valve 1 coacts with a valve assembly generally designated 20 to be more fully described. These two assemblies will be joined into an equivalent cartridge unit when both assemblies are inserted and positioned in the cavity 3 and chamber means 4.

VALVE ASSEMBLY

The valve assembly 20 includes a bridge piece or element 21 and retainer ring 22 as shown in FIGURES 2, 3, and 7 of the drawings.

The bridge piece 21 and retainer ring 22 may be made of any suitable material but in the illustrated form of the invention are preferably formed from plastic material such as those materials sold under the trademarks "Celcon" or "Delrin" made of fluorcarbon resins and assified as acetal copolymers.

While certain plastics have been above designated, it will be understood by those skilled in this art, that any type plastic, resin or similar material may be used for these elements wherein the physical properties provide good resistance against wire drawing; non-water absorption; adaptability to hot and cold water system; tensile strength and dimensional stability.

Thus, any thermoplastic or thermosetting material with the above properties which remains stable and is not adversely affected by constant exposure to air or water between the normal operating and shipping temperatures of -10° F. to +180° F. experienced by the control valve 5 may be utilized for elements of the control valves described herein and more particularly for the elements of the valve assembly.

The bridge piece 21 is a recto-linear member having a pair of spaced downwardly projecting nibs or elements 23 and 24 which are adapted in assembled position to fit into and engage the respective inlet passage 5 and outlet passage 7 at the points where they communicate with the floor of the cavity 3 in the dispensing head 2. Suitable sealing gaskets 25 and 26 are provided about the nibs 23 and 24. Sealing gasket 25 will prevent leakage of fluid into the cavity 3 as is shown in FIGURES 2 and 3 of the drawings.

The bridge piece 21 includes a longitudinal flow passage 27 which connects at one end with an inlet 28 in the nib member 23 in alignment with inlet passage 5 so as to permit fluid from the inlet passage 5 to enter into the longitudinal passage 27 in the bridge piece 21.

The longitudinal passage 27 also communicates with an outlet port 29 centered in a seat means 30 which is formed on the bridge piece 21 substantially medially of the nib elements 23 and 24. The seat means 30 has a beveled or chamfered portion 31 to provide an optimum and effective seal and engagement for valve head 32. mounted for actuation towards and away from the outlet port 29 by the actuating assembly 50 to be hereinafter described.

The bridge piece has an outlet 33 formed therein at the end remote from the inlet 28. The outlet 33 extends through the bridge piece transversely of the line of the longitudinal passage 27 and through the nib 24 so that it is in alignment with the outlet passage 7 in the dispensing head. The end of the outlet 33 remote from the outlet passage 7 will in assembled position communicate with a fluid chamber 34 formed when the control valve 1 is assembled into position in the cavity 3.

When fluid enters this fluid chamber 34 from the sump or chamber 4 it will pass through outlet 33 and outlet passage 7 to the chambers 8 and dispensing outlet 9 in the nozzle member 10 of dispensing head 2 all of which is clearly shown in FIGURE 2 of the drawings.

If the size or diameter of the outlet port 29 in the bridge 50 21 is fixed, then by adjusting or sizing the diameter of the outlet 33 in the bridge piece relative the size of the outlet port 29 and easy and simple means for regulating the range of adjustability of the rate of fluid flow for the volume of fluid delivered by the dispensing head will be provided.

This fixed and variable orifice technique for regulating the range of adjustability of the fluid flow is a well-known expedient. However, in the present invention, the technique is expedited because the bridge piece 21 is made of relative cheap material and the serviceman handling this type cartridge can either have a plurality of bridge pieces with sized outlets 33 therein or alternatively the outlet 33 in the bridge piece can be sized at the smallest required diameter and re bored by hand tools to the desired sized opening by the service personnel when the control valve is installed.

FIGURES 2, 3 and 7 show that the retainer ring 22 is an annular cylindrical member which is flat at one end to fit against the floor of the cavity 3 and sized to enable the ring to fit snugly against the wall of the cavity 3. A groove 35 on the outer wall of the retaining ring 22 receives an O-ring 36 which engages the wall of the cavity 3 and seals against leakage of fluid being dispensed through the control valve 1.

The inner wall of the retainer ring 22 has bracket means 37 and 38 formed at diametrically opposite points 75 thereon by thickened portions on the inner wall along

cord lines relative a given number of degrees of arc as is clearly shown in FIGURES 4 and 7 of the drawings.

The bracket means 37 and 38 have slot means 39 and 40 respectively in the medial portions thereof along the diametral lines of the retainer ring 22 and the slot means are shaped such that they receive in close fit engagement the respective ends of the recto-linear bridge element 21. The slot means 39 and 40 are of a depth just sufficient to bring the lower face of the bridge element 21 and the retainer ring 22 into substantially the same plane so that they will fit in assembled position in snug engagement with the floor of the cavity 3 all of which is shown in FIGURES 2 and 4 of the drawings.

The upper end of the retainer ring 22 is provided with a circumferentially disposed ridge 41 which coacts with the connecting housing 42 of the actuating assembly 50 to hold and seal a diaphragm member 43 therebetween.

The diaphragm member 43 is circular in shape having a diameter approximately equal to the outer diameter of the control valve 1 and will be made of an elastomeric material. In assembled position in the cavity 3, the diaphragm member 43 and the valve assembly 20 delineate the liquid or fluid chamber 34 for the control valve 1.

The liquid or fluid chamber 34 formed by the control valve communicates with the sump or chamber 4 and with the end of the outlet 33 in the bridge piece 20 remote from that end of outlet 33 in communication with the outlet passage 7.

When the valve head 32 is in engagement with the valve seat 31, about the outlet port 29 no fluid will flow through the control valve 1. However, when the valve head 32 is moved out of engagement with the valve seat 31, fluid passes out of the outlet port 29 into the sump 4 and thence to liquid or fluid chamber 34 through the outlet 33 and outlet passage 7 in alignment therewith to the chamber 8 and the dispensing outlet 9 in the dispensing nozzle 10 connected in the dispensing head 1.

An annular washer 44 is also positioned between the upper or outer face of the diaphragm member 43 and the lower or inner face of the connecting housing 42 of the actuating assembly 50.

The annular washer 44 has a laterally extending prong or projection 45 which as shown in FIGURES 2 and 3 will engage a slot or key way 46 in the dispensing head 2.

The annular washer 44 acts to prevent the diaphragm 43 from wrinkling or being otherwise distorted when the respective valve assembly 20 and actuating assembly 50 of the control valve are being assembled in the dispensing head to provide an equivalent cartridge unit.

In order to control the flow of liquid or fluid from the outlet port 29 in the bridge piece 21, the valve head 32 is brought into and out of engagement with the valve seat 31 by the actuating assembly 50 now to be described.

ACTUATING ASSEMBLY

Thus, the actuating assembly 50 includes a yoke member or stirrup 51 having a pair of spaced legs 52 and 53 which clamp a valve head holder 54 therebetween in which the valve head or closure means 32 is mounted, as is shown in FIGURES 2, 3, 4 and 8 of the drawings.

In assembled position, the yoke member 51 fits about the bridge element 21 to permit it to move normal to the longitudinal line of the bridge element. A valve stem 55 formed on the yoke member at the end remote from the point where the valve head is mounted will extend through a medially disposed opening 56 in the diaphragm member 43 and into a spring housing 57 where the threaded end of valve stem 55 receives a spring seat nut 58. In assembled position in the cavity 3, the upper face 59 of the yoke member and the lower face of the spring seat nut 58 will together with the diaphragm disc 60 and lock washer 61, hold the diaphragm 43 and seal against leakage of fluid from the fluid chamber 34 formed in the control valve 1.

It will be noted that the spring housing 57 has an inwardly directed flange 62 which engages an outwardly disposed shoulder 63 on the spring seat nut and that this inwardly directed flange is slideable along the outer surface of the nut to provide a lost motion means for purposes which will appear clear hereinafter.

Mounted in the spring housing 57 between the outer end of the spring seat nut 58 and a range screw 64 is the range spring 65 and about the spring housing 57 and between a shoulder 66 formed on the connecting housing 42 and a laterally extending flange 67 on the spring housing 57 is the push button return spring 16.

By reference to FIGURE 9 an alternate valve seat for the bridge element in accordance with the present invention is shown.

Thus, the bridge piece or element 21' in FIGURE 9 has a longitudinal passage 27' therein which communicates with a centrally disposed hole or passage 100 in turn centered in a boss 101 and having a shoulder 102 formed at the end thereof adjacent to the passage 27'.

The hole or passage 100 will receive therein an annular stainless steel element 103 and this element has a through passage therein forming outlet port 29' which communicates with the longitudinal passage 27' in the bridge piece or element 21'.

A stainless steel insert for an outlet port in the inlet duct member of a control valve similar to member 103 in the present invention is shown and described in my co-pending application U.S. Ser. No. 549,888 and the details and advantages of such stainless steel inserts is therein described in detail and accordingly will not be elaborated on more fully herein.

ASSEMBLY AND OPERATION

The bridge piece 21 and stirrup member 52 and its parts including the valve head 32 are first assembled into operative relation.

The valve assembly 20 is next pre-assembled by setting the bridge piece 21 and coacting stirrup member 52 into the retainer ring 22; the O-ring 36 on the outer wall of the retainer ring and the sealing gaskets 25 and 26 on the nibs 23 and 24.

Then the valve assembly 20 is positioned in the cavity 3 and sump or chamber 4 and the diaphragm 43, annular washer 44 and diaphragm disc 60 and lockwasher 61 connected to this assembly, all as shown in FIGURE 2 of the drawings.

An equivalent cartridge unit is formed when the connecting housing 42 and the associated elements of the actuating assembly 50 are next connected in the cavity 3 as by threading the connecting housing 42 into position and connecting the range spring housing; or range spring nut 58, range spring 65 and range spring screw 64 to the valve stem 55 so as to coact with the valve assembly 20.

In assembled position in cavity 3 in the dispensing head the range spring 65 and the range spring screw 64 will be adjusted to provide the desired setting for operating the control valve. It will be noted that when the spring housing 57 is depressed that it can only travel a predetermined distance and will shoulder against the upper face of the connecting housing 42.

However, by reason of the lost motion connection between the range spring nut 58 and the spring housing 57, the range spring 65 will expand to force the range spring nut 58 and yoke or stirrup 52 connected thereto the desired distance in accordance with the range spring setting.

When the stirrup or yoke 52 moves normal to longitudinal axis of the bridge piece of element 21 since it has a diameter and size less than the size of the sump or chamber means 4, as it uncovers the outlet port 29, fluid will flow into the sump and thence to the chamber 34 as above described.

Since the push button return spring 16 acts between the connecting housing 42 and the shoulder 67 of the

ge spring housing 57 it will normally urge the range housing and the yoke or stirrup 52 connected thereto outwardly. This will in turn cause the valve head to engage the valve seat 31 and maintain the outlet port 29 in the bridge piece 21 normally closed.

Movement of the spring housing 57 is accomplished by push button 15 which is set to engage the upper face of the spring housing 57 in assembled position as shown in FIGURE 2.

Thus, when the push button 15 is depressed, the spring 57 will act simultaneously to compress the push button return spring 16 and permit the range spring 65 to compress and move the yoke or stirrup 52 and the valve head therein out of engagement with outlet port 29. As a result, liquid or water depending on the fluid being dispensed will pass from the inlet passage 5 through the bridge piece 21 into the sump 4 and fluid chamber 34 communicating therewith; thence out of the fluid chamber 34 through the outlet 33 to the dispensing outlet 9 all as above described.

Since the outlet 33 has been sized relative to the outlet port 29 in the bridge piece 21, the volume of water will be controlled as a function of the relative sizes of these openings and the net differential axial forces across the diaphragm member 43.

Thus, a simple effective equivalent cartridge unit is provided in which at least the parts of the valve assembly in contact with the fluid being dispensed are made ofastic or the like materials and of simple construction which is relatively cheap and can readily withstand the erosive and erosive effects of the flow of fluid through the control valve.

Since the plastic parts can be molded easily and simply it is clear that they will be cheaper than the corresponding metal parts which have been utilized heretofore and which required machining and special connections in the control valve to provide a device for performing the same result as is provided by the present invention.

Accordingly, the materials utilized in control valve of the present assembly are cheaper and the assembly is much simpler than heretofore obtainable in the prior art. Further, the advantages of simple replacement of this cheaper device are obvious for the servicing of these units.

What is claimed is:

1. A control valve to be mounted in a dispensing means for a fluid dispensing system comprising:

- (a) a valve assembly made of plastic material having an inlet connected to a source of fluid to be dispensed, and an outlet port;
- (b) a diaphragm member;
- (c) an actuating assembly including means coacting with said valve assembly to open and close said outlet port and to hold said valve assembly, diaphragm and actuating assembly together to form an equivalent cartridge unit;
- (d) said valve assembly including:
  - (1) an elongated bridge element having a longitudinal passage therein;
  - (2) said inlet communicating with one end of the longitudinal passage and said outlet port communicating with the longitudinal passage at a point medially along the bridge element;
  - (3) and a retaining ring having bracket means operatively associated with the bridge element to hold the same in assembled position in said dispensing means;
- (e) said bridge element having an outlet extending transversely of the longitudinal line of the bridge element and in assembled position connected to deliver fluid from said control valve to the dispensing means;
- (f) and the diaphragm and valve assembly in assembled position in said fluid dispensing system disposed to form a fluid chamber in said control valve to pro-

vide communication between said outlet port and said outlet in the bridge element for fluid to be dispensed.

2. In a control valve as claimed in claim 1 wherein the outlet in said bridge element is sized relative to the outlet port in the bridge element to regulate the range of adjustability of the fluid flow in the fluid dispensing system.

3. In a control valve as claimed in claim 1 wherein the bracket means in the retaining ring comprises:

- (a) spaced slots of predetermined size;
- (b) and said bridge means fits into and coacts with the slots to position the bridge in assembled position.

4. A valve assembly for a control valve in a fluid dispensing system comprising:

- (a) a bridge element;
- (b) a retainer ring;
- (c) bracket means on said retainer ring;
- (d) means in said bracket means operatively connecting the retainer ring and bridge means to hold the bridge means in a predetermined position in the control valve;
- (e) said valve assembly made of a plastic material.

5. In a valve assembly for a control valve as claimed in claim 4 wherein said plastic material is from the class of acetal copolymers.

6. In a valve assembly for a control valve as claimed in claim 4 wherein:

- (a) said bridge element has an elongated recto-linear shape;
- (b) the retainer ring is annular and the bracket means thereon includes at least two members disposed at diametrically opposite sides thereof;
- (c) each of said members has a slot means of predetermined size and the bridge means fits in the slot means in assembled position.

7. In a valve assembly for a control valve as claimed in claim 4 wherein:

- (a) the bridge element has an inlet connected to a source of fluid to be dispensed;
- (b) an outlet port for said bridge element for passing said fluid into said control valve;
- (c) and the bridge element having an outlet sized relative to the outlet port to regulate the range of adjustability of the rate of fluid flow delivered by the control valve.

8. A bridge means for the valve assembly in a control valve comprising:

- (a) an elongated recto-linear shaped member having means forming an inlet to be connected to a source of fluid to be dispensed and an outlet port for said fluid;
- (b) said bridge means having an outlet passage in communication with said outlet port for delivering fluid to be dispensed by said control valve;
- (c) said outlet passage sized relative to said outlet port to regulate the range of adjustability of the rate of fluid flow dispensed by the control valve.

9. In a bridge means as claimed in claim 8 wherein the member is made of a plastic material.

10. In a bridge means as claimed in claim 9 wherein the plastic material is from the class of acetal copolymers.

11. A retainer ring for the valve assembly in a control valve comprising:

- (a) an annular member having an inner wall and an outer wall;
- (b) supports on the inner wall of said annular member including at least two bracket means disposed in spaced relation;
- (c) each of said bracket means having radially extending mounting means formed therein;
- (d) and means in the outer wall of the annular member to provide a seal for the valve assembly in assembled position in the control valve.

12. In a retainer ring as claimed in claim 11 wherein the mounting means comprises slots of predetermined and sized dimensions disposed on the inner wall substantially transversely with respect to each other.

13. In a retainer ring as claimed in claim 11 wherein the annular member is made of a plastic material.

14. In a retainer as claimed in claim 13 wherein the plastic material is from the class of acetal copolymers.
